UNITED STATES PATENT OFFICE.

JOSEPH A. MARTOCELLO, OF PHILADELPHIA, PENNSYLVANIA.

COMBINED COUPLING AND VALVED OUTLET.

Application filed December 3, 1921. Serial No. 519,597.

To all whom it may concern:

Be it known that I, JOSEPH A. MARTOCELLO, a citizen of the United States, residing at Philadelphia, Pennsylvania, in the county of Philadelphia and State of Pennsylvania, have invented a certain new and useful Combined Coupling and Valved Outlet, of which the following is a specification.

10 My invention relates to outlets for the air connections to ice cans from the air laterals of ice freezing systems.

The main purpose of my invention is to combine an air lateral coupling with a valved outlet so as to obtain closer connection and better protection of the outlet and valve.

A further purpose is to make the valved outlet from an air lateral more compact and at the same time to simplify and cheapen it.

20 A further purpose is to provide a four-way outlet for the air lateral, distributing from each connection into four cans, and thus increasing the service from each connection.

25 A further purpose is to improve the bracket support for an air pipe.

A further purpose is to support the connection which receives the terminal from the flexible pipe directly from the air pipe, as distinguished from supporting both from the bracket.

30 A further purpose is to combine a connection for the terminal of the flexible air pipe, and an inlet for a steam needle in a single structure.

35 Further purposes will appear in the specification and in the claims.

I have preferred to illustrate my invention by one form only among the various forms in which it may appear, selecting a form which is practical, highly efficient, compact and inexpensive, and which at the same time well illustrates the principles of my invention.

40 Figure 1 is a vertical longitudinal section through my valved coupling, taken upon line 1—1 of Figure 2.

45 Figure 2 is a top plan view of the structure seen in Figure 1.

50 Figures 3 and 4 are sections upon lines 3—3 of Figure 1, and 4—4 of Figure 2 respectively.

Figure 5 is a top plan view of a four-way

form of my invention upon a smaller scale than in Figures 1—4.

55 Figures 6 and 7 are sections upon lines 6—6 of Figure 5 and 7—7 of Figure 6, respectively.

Figure 8 is a fragmentary top plan view of an installation to which my four-way 60 valve is applied.

Figure 9 is a section upon line 9—9 of Figure 8.

In the drawings similar numerals indicate like parts.

65 In the valved connection of air pipes with air laterals, compactness, from the standpoints of economy of space and cheapness of manufacture, strength as affected by extent of projection and the stiffness of the 70 intervening support, and reliability of service are all material and may in different structures or for different uses prove controlling. It is very desirable to combine the air control with the air cut-off in order 75 that a single valve may perform both functions, and it is also desirable that all cut-off valves be located at the tapping point, as distinguished from some other point along the path from the lateral to the air 80 pipe within the ice can.

I have aimed to secure strength, compactness and reliability in a structure embodying one or more outlets and valves capable of use to control, to cut off or for both purposes, and at the same time to reduce the 85 number of tapping points, where desired.

Explaining the construction shown in description and not in limitation:—

The air lateral 10 passes between a number of ice making cans 11, as usual and is tapped to supply air to pipes 12 in these cans. In the form shown in Figures 1—4 but two outlet connections 13 are shown from each tapping point, whereas in the 95 form shown in Figures 5—8, four such outlets for hose connection are provided.

90 In each case the lateral is tapped by interplacing a coupling 14, threaded at each end, between facing threaded ends 15 of sections of pipe 10 making up the lateral. The coupling is provided with a lateral air passage 16, upwardly extending in the illustration, with which communicate oppositely extending "inlet" passages 17, two in number and opposite in Figures 2—4, and four in 100 105 Figures 5—8.

number at quadrants in the form shown in Figures 5-8.

These passages 17 connect with tapered valve openings or seats 18, which in Figures 1-4 are two in number and have parallel axes, and in Figures 5-8 are four in number, comprising two pairs at right angles to each other, the two of each pair having parallel axes.

10 These passages 17, are considered "inlet" passages because they lie on the inlet sides of the valves. They are preferably in line in each pair with blow-out passages 19, two in number in the one form and four in 15 number in the other, to correspond with the number and position of the inlet passages 17.

Each of the outlets 13 for hose connection is pierced by an outlet passage 20, which terminates at each valve opening in the 20 illustration nearer to the connection of the outlet passage 19 with the valve opening than to the connection of the inlet passage therewith, in order to co-operate with the plug valve 21 shown, so that the plug valve 25 may afford a nice adjustment of the quantity of air passing through the valve, act as a trap for dust and dirt carried by the air, and turn from the position selected for 30 graduated air passage to a blow-out full opening for discharge of the dust and dirt to the atmosphere without further air opening to the outlet but with an intermediate position in which the valve is wholly closed.

This valve plug construction includes a 35 through passage 22, which in blow-out positions will connect the inlet passage 17 of the valve with the blow-out passage 19, and a branch passage 23 from this through passage, which connects with the circumference 40 of the plug at a point preferably nearer to one end of the through passage than to the other end of this passage.

Because I desire to insert the plugs having parallel axes from opposite directions 45 the two plugs of each pair are shown in the sectional Figures 1 and 6 as opposite counterparts though in fact identical; and the opposite direction of extension of the terminals 13, and of all of the inlet and blow- 50 out passages makes these parts of my construction in the sectional views also appear as opposite counterparts. However, considered as separate units, each of these 55 valves considered in conjunction with its inlet, outlet and blow-out passages is identical with each other.

The valve structure herein shown, along with the inlet, outlet and blow-out passages and combinations are described and claimed 60 by me in an application for valve for air supply to ice cans, filed October 24, 1921, Serial Number 509,894, in which its operation is described at greater length, but in 65 which there are two such valves only for each air lateral connection. These two out-

lets feed two cans, as contrasted with four valves, arranged as two pairs of valves, feeding four cans as shown in Figures 5-8.

To complete the description I will state briefly that the valve plugs shown in Figures 1 and 6 are shown in the position to which they have been opened to feed a desired quantity of air into the individual cans, the quantity of air fed being increased by turning the plugs at the left in clockwise direction and those at right in counter-clockwise direction in the illustration; remembering, however, that in each case the actual direction of turning from the end to which the wrench is applied would be the same. In the positions shown any dust or dirt carried by the air will fall to the bottom of the through passage, being assisted in this by the enlarged cross-section of the plug passages as compared with the restricted opening through which the air passes from the inlet passage to the plug and from the plug to the outlet passage, giving a relatively low speed of air flow through the plug.

Counter-clockwise movement of the plugs at the left and clockwise movement of the plugs at the right result in reducing and finally cutting off the flow of air and, if continued, bring the through passages in line with the inlet and blow-out passages, respectively, in each valve for blow-out purposes.

The location of the inlet and blow-out passages in line with each other permits 100 drilling of these passages at one operation and, with these passages for the two valve structures of a pair in line, permits drilling of the two inlets and two blow-out passages at one operation if desired; though 105 this would ordinarily not be done because of the accentuation of any error in setting.

It will be evident that my four-way feature could be applied not only to valves combining with a coupling for their air 110 connection with the air lateral, but to valve structures having a hollow stem adapted for insertion within the lateral or for connection therewith and in which hollow of the 115 stem corresponds to the passage 16, using the valves either above or below the lateral as explained in my said application.

In the valve structures shown, the plug is turned by connection of a wrench with a non-circular plug terminal 24 which terminal is preferably of irregular cross-section so that the wrench may engage with the end of the plug in one position enabling the operator to judge of the placing of the valve parts within the plug by the direction of extension of the wrench handle. A cylindrical end flattened at one side at 125 is shown as one form of this.

The valve plugs are held in place conventionally by washers 26 and screws 27 located 130

at the smaller ends of the plugs. Where the two-way form of valve is used the valves can be located closer together than in the four-way form since they need be spaced far enough only to give room for walls 28 between the passage 16 and the openings forming seats for the valve plugs. As this gives quite a little spacing in any event, I take advantage of the corresponding exterior length of the structure at this point for a transverse strengthening and stiffening rib 29 about and above the side walls 30, 31 of what may be termed the valve body 32 of my combined coupling and valved outlet. The stiffening rib 29 need not be carried about the coupling. The rib is shown as flared at the top at 33 to about the width of the coupling.

A longitudinal stiffening rib 34 is shown which is given greater width at the ends at 35. The ends of the coupling are strengthened at 36 as is usual.

The body of the valve portion of my combination need not be wider than the normal length of the plug valves giving just enough metal between the sides 30 and 31 and the passage 16 to insure strength and avoid leakage.

In the form shown in Figures 5-8 the valve body comprises two portions each similar to the one shown in Figures 1-4 but at right angles to each other, to receive the two pairs of valve plugs and to provide for the two pairs of oppositely facing outlets at right angles to each other. In each valve pair the plugs require a little more spacing than in the single-pair form because more air is to be handled, requiring a larger passage 16' and the intervention of a transversely disposed body for the other pair requires additional room.

Though I have shown the valved outlet portion of the combination as above the coupling and the great strength of my combination makes it possible to locate the outlet above the lateral with much greater safety than in the case of outlets which are merely tapped into the air lateral and the upper position is a more convenient one for connection of the flexible pipes leading to the ice cans, it will be evident that the coupling and outlets could be reversed in position, preferably with reversal of the valve plug relations as in the form shown in my above mentioned application where the valve lies below the lateral, and I wish to be understood as providing for either construction. For a like reason, where it is not desired to use gravity in the plug for the purpose of trapping dust and dirt within the valve, to be blown out subsequently, the valve structure could be located at either side of the lateral.

It will be obvious that the particular structure of the valve and the character

of strengthening ribs, etc., provided is not material to the broader aspects of my invention herein but that the coupling and valved outlets or the four-way outlet from a single tap, with or without the combination of 70 the coupling may be used with other forms of valve and other detail of the structure to practice my invention in whole or in part.

In Figures 8 and 9 I show a convenient bracket 37 comprising a hook member 38 75 preferably bearing on the inside at the bottom 39 only and relieved at the outside as at 40 to provide for easy removal with very slight lifting of the bracket. In order to reduce the danger of freezing against the 80 inside of the can I hollow out the lower part at the contact 39 so as to have the actual contact along one or more edges 41 only.

The bracket is intended to engage an edge of the can and to be placed at any desired 85 position along the side or end. Obviously it is suited for vertically or diagonally placed pipes 12 according to the construction of the holding mechanism used. I have shown it as applied in holding vertical pipes 90 and have adapted the pipe to pass through the bracket sufficiently so that the fitting 42 is supported from the pipe and its air tight engagement for through passage of the air to the can is in no way affected by the structure of the bracket. A convenient way of 95 holding the pipe in the bracket and allowing it to pass through the bracket is shown in the threads 43 by which it may be supported with any desired amount of extension above 100 the bracket.

The fitting 42 cooperates with the tapered terminal nozzle 44 carried by the hose 45 and forms a metallic seal for this nozzle at the same time that it is adapted to receive 105 the steam needle for releasing the pipe from the ice of the can. I thus simplify the construction considerably by using but one fitting for both these purposes, obtain a metallic fit and seal and free the air seal between the nozzle and the pipe from all complication of bracket structure. The nozzle could pass through the fitting into the pipe if desired.

I purpose including herein all such 115 changes as may be made by others skilled in the art in view of my disclosure herein and which are reasonably within the scope of my invention.

Having thus described my invention, what 120 I claim as new and desire to secure by Letters Patent is:

1. A combined coupling and valved outlet comprising a coupling threaded for pipe engagement and providing a passage opening laterally therefrom and having tapered valve seats in communication with the passage on opposite sides thereof, with parallel axes and having the taper facing in different directions, in combination with independent 125 130

tapered plug valves therefor, operated from different sides and hollow terminals for hose connection having their axes parallel with that of the coupling and brought in communication with the passages by the respective valves.

2. A combined coupling and valved outlet comprising a coupling threaded for pipe engagement and providing a passage opening laterally therefrom and having tapered valve seats in communication with the passage on opposite sides thereof, with parallel axes and having the taper facing in different directions, in combination with independent tapered plug valves therefor, operated from different sides and hollow terminals for hose connection brought in communication with the passages by the respective valves, the outlet being provided with blow off passages for the several valves.

3. A combined coupling and valved outlet comprising a coupling threaded for pipe engagement and providing a passage opening laterally therefrom and having tapered valve seats in communication with the passage on opposite sides thereof, with parallel axes and having the taper facing in different directions, in combination with independent tapered plug valves therefor, operated from different sides and hollow terminals for hose connection brought in communication with the passages by the respective valves, the outlet being provided with blow off passages

for the several valves, in line with each other and with the communication between the lateral passage and the valve seats.

4. A valved coupling and outlet, comprising a coupling having coaxial threaded openings, one at each end to receive pipe sections and having a lateral passage, in combination with a pair of valves connected with said passage and having oppositely extending outlets from said valves parallel with the axis of the threaded connections.

5. A combined coupling and valved outlet, comprising a coupling having coaxial threaded openings for connection with oppositely extending pipe sections, and a lateral passage, in combination with a pair of valves spaced in the direction of the length of the pipe and connected with said passage, outlets from said valves and blow-out connections from said valves in line with the connections of said valves with said passage.

6. A coupling and valved outlet, comprising a coupling fitted to unite pipe sections, a common lateral passage supplied from the pipe sections, a pair of oppositely facing outlets and oppositely facing valves for the outlets operated from opposite sides of the coupling and controlling flow of fluid from the common passage to the respective outlets, the valves having connections with the lateral passage and blow-off passages in line.

JOSEPH A. MARTOCELLO.
